DEEP HAIR WAVING DEVICE

Holger Lingard, New York, N. Y.

Application April 3, 1934, Serial No. 718,747

3 Claims. (Cl. 132—41)

This invention relates to improvements in hair wavers designed to be worn by the user, and its leading object is to provide a hair waver having a thin wire-like rod insertable in the hair of the user, and a looped frame hinged thereto, which is adapted to cooperate with the rod to form the wave, together with means for arching the rod within the looped frame, so as to displace the hair between the two, and form a relatively deep wave.

Another object of the invention is to provide a waver for the hair of women, wherein one of the wave forming jaws or members is formed with a hair retaining loop, and the other member is adapted to be displaced within the loop, so as to form a deep hair waving crease in the hair, the two members being connected to each other by a hinge lever device, by means of which the user may displace the loop receiving member, by a one hand operation.

With the above and other objects in view the invention relates to certain new and useful constructions, combinations, and arrangements of parts, clearly described in the following specification, and fully illustrated in the drawing accompanying; in which:—

Fig. 1 is a perspective view showing the waving device applied to the head of the user.

Fig. 2 is a perspective view on an enlarged scale showing the device opened.

Fig. 3 is a side elevation thereof showing the device closed.

Fig. 4 is a detailed side elevation enlarged, shown partly in section.

Fig. 5 is a detail end view of the displaceable rod.

Referring to the drawing accompanying herewith, 5 designates a wire-like rod or compressor frame member, which is arched to conform to the shape of the average human head. This member or flexible wire rod is formed with a lateral loop 6, which forms a hair stop for limiting the sliding movement of the hair against the rod, when the same is inserted under the hair of the user. The adjacent end portion 7 of the rod is then extended at approximately right angles to the direction of the member 5, and is then formed to provide a T-shaped terminal 8.

The flexible rod 5 is rigidly clamped to the sheet metal lever handle 9, by means of the S-shaped terminal 10 thereof. The T-shaped end 8 of the wire rod 5 is inserted in the loop 10a of said terminal 10, which is closed tightly upon the same, so that the lever handle will not move.

The other loop 10b of the lever handle receives the cross bar 11 of the looped frame link 12, so that the latter will hinge freely in said loop 10b. This frame includes the side bars 13 and 14, which are formed with opposing eyes 15 and 16, which receive the end cross bar 17a of the hair loop receiving frame or waving jaw 17. This frame or jaw includes the side bars 18 and 19, which are arched in approximately the same curvature as the flexible rod 5. The ends of the bars 18 and 19 are connected to each other by the cross bar 20, and the ends of the small connecting frame 12 are connected by the cross bar 12a.

The frame or jaw 17 carries on its outer end 15 a terminal retaining element 21, which consists of a U-shaped sheet metal part folded upon the cross bar 20 and clinched thereto, and provided with a small pocket the mouth of which faces the hinged end of the frame or jaw.

The frame or jaw 17 is hinged on the connecting frame 12, which is also hinged to the lever handle 9, the latter being rigidly connected to the flexible jaw or bar 5, in the manner previously explained.

In using the device the flexible rod or bar 5 is pushed under the hair until the hair engages the stop 6. Then the jaw frame 17 is swung over and the offset terminal 5a of the rod 5 is pushed into the pocket of the retaining element 21. When this is done the lever handle 9 will occupy an angular position with reference to the frame 12. When the frame 17 is swung over and against the hair, to be coupled to the end of the bar 5, the hair will be clamped between the two jaws, 5 and 17. By pressing the lever handle 9 toward the frame 12, which also acts as a lever, the S-shaped end of the lever handle will be swung under the frame 17, thereby increasing the arch of the bar 5, which will force the hair between the side bars 18 and 19 of the jaw frame 17, consequently increasing the pressure of the waver upon the hair, and forming at the same time a deeper hair wave.

Having described my invention I claim as new:—

1. A hair waving device consisting of an elongated frame comprising side bars and connecting end bars providing a hair receiving space between said side bars, a lever member pivotally connected to one of said end bars and provided with an inwardly extending portion, a link member pivotally connecting with said inwardly extending portion, and a compressor frame connecting with said link member and having a ter- 55

5 minal adapted to have latching engagement with the frame, whereby said compressor member will be arched between the side bars of said frame member when the link and lever members are moved toward each other.

2. A hair waving device consisting of a frame comprising side bars and end bars spacing said side bars from each other, a link frame having side bars and end bars connecting said side bars, 10 said link frame also having bearings intermediate of its ends located for said side bars in which

one of the end bars of the frame is pivotally connected, a lever pivotally mounted on said link frame, and a compressor bar rigidly connected with said lever and adapted to swing between the side bars of the first frame, said compressor bar having latching engagement with said first frame. 5

3. The construction set forth in claim 2, the compressor bar having an outstanding hair stop formed thereon to limit sliding of hair. 10
